UNITED STATES PATENT OFFICE

103,554

DESIGN FOR A CLOCK-CASE

William K. Sessions, Forestville, Conn., assignor
to The Sessions Clock Company, Forestville,
Conn., a corporation of Connecticut

Application February 1, 1937, Serial No. 67,374

Term of patent 7 years

To all whom it may concern:

Be it known that I, William K. Sessions, a citizen of the United States, residing at Forestville, in the county of Hartford and State of Connecticut, have invented a new, original, and ornamental Design for a Clock-Case, of which the following is a specification, reference being had to the accompanying drawing, forming part thereof.

Fig. 1 is a perspective view of a clock-case showing my new design;

Fig. 2 is a front elevation thereof;

Fig. 3 is an end elevation thereof; and

Fig. 4 is a sectional view on the line 4—4 of Fig. 2.

The design is characterized by the case having a pair of spaced-apart end-plates with a main body-portion between said end-plates, each of two opposite ends of the body-portion being curved rearwardly and interrupted by two grooves forming between them a rounded colonnette extending between the said pair of end-plates.

I claim:

The ornamental design for a clock-case substantially as shown and described.

WILLIAM K. SESSIONS.
